UNITED STATES PATENT OFFICE.

JAMES W. PHELPS, OF CHICAGO, ILLINOIS, ASSIGNOR TO SOLAR ELECTRIC COMPANY, OF CHICAGO, ILLINOIS, A CORPORATION.

DESIGN FOR AN ELECTRIC-LAMP GLOBE.

No. 39,323.

Specification for Design.

Patented May 26, 1908.

Application filed December 8, 1906. Serial No. 346,997. Term of patent 14 years.

To all whom it may concern:

Be it known that I, JAMES W. PHELPS, a citizen of the United States, residing at Chicago, in the county of Cook and State of Illinois, have invented a certain new, original, and ornamental Design for Electric-Lamp Globes, of which the following is a specification, reference being had to the accompanying drawing, forming a part hereof.

In the drawing, Figure 1 is a side elevation of an electric lamp globe showing my new design. Fig. 2 is a plan view thereof.

The essential feature of my design consists of an electric lamp globe in the form of an oblate, ellipsoid or canteen-shape with a neck portion at its edge or in line with one of the major axes.

I claim:

The ornamental design for an electric lamp globe, as described and shown.

JAMES W. PHELPS.
